ELECTRIC CALENDAR

Reginald J. Sharpe and Edward Pekonen, Chisholm, Minn., assignors of one-third to Hjalmar Paulson, Chisholm, Minn.

Application January 31, 1934, Serial No. 709,203

11 Claims. (Cl. 40—111)

This invention relates to electric circuits for automatically operated calendars.

One important object of the invention is to provide simple automatic electrically controlled mechanism to compensate for months of different lengths during a year, and for leap years.

Other objects and advantages will appear in the further description of the invention.

Referring now to the accompanying drawings 10 forming part of this application and wherein like reference characters indicate like parts:

Figure 1 is a combined wiring diagram and schematic view of one embodiment of the invention.

Figure 2 is an elevation of the year dial for control of the month indicating circuit.

Figure 3 is an enlarged section on the line 3—3 of Figure 1 of the ratchet joints intermediate of the day and date shaft, and between the auxiliary 20 motor and date shaft.

Figure 4 is an enlarged diagrammatic view of the contacts and spacings of a portion of the year dial.

Figure 5 is a further plan view, partly in section, of the exhibitor mechanism, showing the direct relation of the motors thereto.

Figure 6 is an elevation of one of the alternately operable contacts of which there are two pairs associated with the exhibitor shafts.

Figure 7 is a wiring diagram of a modified circuit for operating the device.

Our present invention relates to that type of periodically driven calendar such as illustrated in our copending application, Serial Number 35 601,018, and in which either an endless tape, drum or disc, form of exhibitors may be employed, and for convenience of illustration in our present application we have shown the tape form as being operated about suitable rollers.

The periodic device, in this instance, is illustrated as a clock mechanism, indicated at 1, and the tape operating rollers which control the exhibitor means are illustrated at 2, 3 and 4, they being designed to represent the day of the week, 45 the date of the month, and the month, respectively.

One novel feature of the present invention is that the day and date exhibitor means are operated in conjunction and simultaneously part 50 of the time, and independently at other times to compensate for short and long months and leap years.

Another novel feature of the invention is that the three different exhibitor means may be each 55 operated by a separate and independent motor,

those at present employed for such purpose being synchronous self starting clock motors, common in the art.

The alternating current power circuit source for operating the device is illustrated at 6 and 7, and which may or may not actuate the periodic device or clock as preferred, and depending upon the use to which the invention is put. However we have illustrated in conjunction with the clock the rotary switch disc 8 mounted upon the shaft 10 5 and which shaft in this instance is so connected and operated by the clock as to rotate once in every 48 hours. This disc 8 is provided with two contact points 10 and 11, adjacent the peripheral edge thereof and with a brush contact illustrated 15 at 12 which is common to both of the contacts 10 and 11. From the contact 12 the wire 13 leads to the day and date operating motor 14, the opposite side 15 of which is connected to the wire 6 of the power line. Straddling one side of the disc 8 20 is the insulated contact support 16 carrying the opposed reciprocal contact pins 17 and 18, each engaging and being held in place by a spring member 19 the fixed ends of which are each held against the support 16 as by a suitable screw 20 25 which forms a connection for the wires 21 and 22 leading therefrom to alternately operated switches 23 and 24, which latter are controlled by the rotation of the day of the week exhibitor shaft 25. Now it is to be understood that the shaft 25 is 30 connected to and operated by the day and date motor 14, as more clearly illustrated in Figure 5 of the drawings. It is apparent that as the contact disc 8 is operatively connected with the clock so that it makes one revolution in 48 hours it will 35 close one or the other of the circuits to the day and date motor every 24 hours. The drum 2 for operating the exhibitor is illustrated as being mounted directly upon the operating shaft 25, and its relation to the exhibitor means, in this 40 instance shown as being a tape 61, is such that the days of the week are progressively exhibited at each half revolution of said shaft and drum.

The shaft 25 is connected to and operates the shaft 27 which carries the date exhibitor operating drum 3, such connection of the two shafts, however, being of the over-running clutch type, as clearly illustrated in Figure 3, the ring 28 being carried by and fixed to the shaft 25, while the double eccentric ratchet 29 is fixed to the shaft 27, thus when the shaft 25 and its ring 28 are traveling in a clockwise direction, the spring controlled pawls 30 will function in carrying the cam 29 with the shaft 27 and date drum 3 therewith. This, however, provides means whereby the date 55

drum and shaft 27 may be rotated in advance of the rotation of the shaft 25, thus providing automatic selective means for independent rotation in one direction of the shaft 27.

5 The shaft 27 is also directly connected, for example, as by the worm 31 and worm wheel 32, to the shaft 33 upon which is fixed the year dial 34; the shaft 33 also being connected to and driving as by the properly ratioed spur gears, the 10 leap year disc 35, so that normally at each one-half rotation of the shaft 27 the year dial moves 1/372 of a rotation, as obviously it must move in step with the date tape which must be capable of exhibiting the maximum of thirty-one days 15 in any month, thus necessitating the year dial being divided into twelve months of 31 days or spaces each. For convenience of illustration we have shown the year dial as having three separate, radially spaced, circumferential series of 20 contacts for opening and closing the circuit to the month motor 36 and the auxiliary motor 37; this being more clearly illustrated in Figure 4 of the drawings wherein the spacings and relative location of the contacts is clearly shown.

25 36 represents the month motor which progressively operates the month exhibitor roller 4, it having associated therewith, as upon the shaft 38, a pair of alternately operated switches 39 and 60, similar in all respects to the switches 24 and 30 23 associated with the day exhibitor means, and which switches function as a secondary control for the motor 36; its primary control being accomplished by association with the contacts on the year dial. The control wires from the motor 36 to the dial are illustrated at 40, 41 and 42, while the connection beyond the dial is that of the wire 7, and beyond the motor that of the wire 6.

40 The auxiliary motor 37 is connected as by the wire 43 on one side to the main line 6 and on the opposite side by the wire 44 through an adjustable contact shoe 45 to the leap year disc 35, the opposite side of said disc being connected as by the wire 46 to the year dial where it is engaged 45 by the outermost circumferential series of contacts on said dial. The wires 41 and 42 for control of the month motor are associated with the intermediate and innermost series of circumferential contacts on the year dial.

50 It will be noted by viewing Figure 2 of the drawings that the months of April, June, September, November and February, as indicated on the year dial, each carry two contact points thereon; whereas the months of March, May, 55 July, August, October and December and January, each carry but a single contact point on the dial. Also it will be apparent that the wire 46 which indirectly controls the auxiliary motor engages only the outermost series of contacts on the year dial, while the wire 41 engages only the intermediate series of contacts, and the wire 42 only the innermost series of contacts; the hub contact 47 of the dial being common to all of the circumferential contacts and connected with 60 the wire 7 of the power circuit.

65 The alternately operated switches shown in connection with both the day exhibitor and the month exhibitor are accomplished by installation of a pair of eccentrics upon the exhibitor shaft; 70 for this explanation, say the shaft 25—(see Fig. 6.) The eccentrics are illustrated at 48 and 49, their maximum and minimum diameters being directly opposite so that the contact pin 50 of one switch is completely depressed forcing the 75 spring contacts 51 and 52 together while the like

pin on the opposite switch is fully retarded, allowing the like spring contacts to separate ready for the subsequent functioning of the contact disc 8, previously described, and while such illustration is shown for convenience in tracing the operation of the device it is apparent that other forms of accomplishing a similar alternate switching of the circuit may be resorted to.

Having thus described the various elements and their cooperative relation necessary to function properly, we will now proceed to describe one cycle of operation of the device; and for which purpose we will assume that the mechanism is properly set with the exhibitors showing Monday, the 1st day of January of any year immediately prior to a leap year, and that the clock is in motion, rotating the disc 8, as previously described, once in 48 hours. The contacts 10 and 11 being so arranged in relation to the clock mechanism, that one or the other will contact either pin 17 or 18 at midnight of each 24 hour period and thus complete the circuit including the wire 21 to the switch 24, held closed by previous action of the shaft 25, thus completing one of the circuits to the day and date motor which will cause said motor to function in rotating the shaft 25 a half revolution at which time the switch 24 will be opened, breaking the circuit, stopping the motor and stopping the rotation of the shaft 25, and closing the switch 23 by action of eccentric 49, ready for subsequent action of the motor. During this half rotation of the shaft 25 the day exhibitor is changed to Tuesday, together with the date exhibitor being changed to the 2nd, and through the action of the worm 31 and worm wheel 32 the shaft 33 of the year dial will be rotated one step of the 31 steps indicated on the dial for each month; and also the leap year disc will be moved one step, it obviously rotating but once in four years. This operation 40 is repeated at midnight of each day until the 31st of the month is reached.

When, however, midnight of the 31st arrives, it will be noted that by virtue of the contact associated with the wire 41 engaging the intermediate series of contacts, engaging that contact opposite the first day of February, and closing that side of the circuit to the month motor 36 causing it to function in rotating the month drum 4 a one-half revolution, thus bringing the 50 month of February into view on the exhibitor, while by reason of the cam action upon the twin switches 39 and 60 the circuit to the motor is opened and the motor stopped. Now the respective days and their corresponding dates of the month will be consecutively exhibited all during the month of February, exactly as previously described for the month of January, until the contacts opposite the month of February in the outer and intermediate series of contacts reaches 60 and engages the terminals of the wires 46 and 41. Now these contacts are positioned so that they will be reached at midnight of the 28th of February, to normally again close the circuit to the month motor 36 advancing the month exhibitor 65 as previously described to indicate the succeeding month of March. Simultaneously with this change in the month exhibitor, it will be noted that the circuit 43, 44 and 46 of the auxiliary motor will be closed by virtue of the contact at 70 the dial terminal of the wire 46 engaging the contact 54 in the outermost series of contacts on the dial, which contact covers the three spaces of the dial from the 28th to the 31st, and which closes the circuit to the auxiliary motor. As 75

the auxiliary motor, as clearly illustrated in Figure 5, is geared through a pawl and ratchet connection 62 to the date exhibitor shaft 27, it will rotate same in advance of and independently of the day exhibitor drum and shaft, by virtue of the over-running clutch, previously described, thus causing the date exhibitor to be advanced from the 28th to the 1st without changing the day exhibitor, because this contact remains closed until the further rotation of the year dial has separated same, and thus stopping the motor, so that at the subsequent functioning of the mechanism the day, date and month exhibitors will be correct.

15 The mechanism then continues to function for the 31 days of March, or until the contact for the month of April in the intermediate series of contacts functions in conjunction with the wire 41, thus closing the opposite side of the circuit 20 to the month motor, which will again advance the month exhibitor drum a half turn, bringing April into view.

Now the proper consecutive showings for the months of April commences, and, it being a thirty day month, a repetition of the action just described will continue until engagement of the contacts on the outer and intermediate series of contacts on the dial will function in connection with the circuit wires 41 and 46, such contacts occurring on the 30th spacing on the dial opposite the month of April so that the auxiliary motor is again caused to function in advancing the date exhibitor one step beyond the day exhibitor shaft. During this action, when the date exhibitor is moved from the 31st to the 1st, the month motor will move the month exhibitor to show the month of May; and thus the calendar will then show the proper day, date, and month.

This functioning obviously continues throughout the year, compensating for long and short months until the 28th day of the month of February in the following year, which is leap year, is reached, when, it will be noted that the leap year disc 35 will have been rotated by all former actions of the day, date, and year mechanisms, thus bringing into action the interrupter 55 on the leap year disc, and this being timed to occur on the 28th day of February each leap year will hold said circuit open and prevent action of the auxiliary motor until midnight of the 29th, thus leaving the date exhibitor showing the 29th, which compensates for the extra day in leap year; but at midnight of the 29th the circuit to the auxiliary motor is closed which carries the date exhibitor from the 29th to the 1st.

In the modified circuit shown in Figure 7 there is illustrated four switch controlling cams, the ones shown at 63 and 64 being mounted upon a shaft 65 operated by the day and date mechanism and the auxiliary motor, and which shaft 65 rotates once a month, and the cam 66 is illustrated as mounted upon the shaft 67 driven by the month motor and which motor indirectly operates the leap year disc 68 which is mounted upon the shaft 69 and by any desired arrangement of gearing is caused to rotate one revolution to every four revolutions of the year disc 66.

Now the principal object of this somewhat simplified circuit is to insure positive non-sparking action of the contacts and to overcome the necessity of critical spacing of the electric contacts, together with the convenience of setting, adjusting, or repairing different units of the mechanism separately.

75 In conjunction with the notched switch con-

trolling discs 63 and 66, the former being to compensate for long and short months in controlling the date tape, and the latter for the short months in controlling the month tape, we have illustrated series of snap spring switches, that series in connection with the disc 63 being illustrated at 70 and that in connection with the disc 66 being illustrated at 71. Like snap spring switches are illustrated at 72 in conjunction with the disc 64, and at 73 in connection with the leap year disc 10 68; these latter being similar to the switches controlled by the date exhibitor means previously described, except that but one such switch, 74, is employed in connection with the month exhibitor shaft 75. The day exhibitor shaft is illustrated at 76, and the periodic clock controlled switch at 77 which may be identical with that illustrated in Figure 1 of the drawings, and the two sides of the main electric circuit are shown at 78 and 79, and the operating motors at 80, 81 and 82. 15 20

The regular daily operation of this modified device is substantially identical with that illustrated in the other figures and on midnight of each day, the periodic switch 77 is thrown completing the circuit through switches 83 or 84 to 25 the day and date motor 80 causing it to operate and move the day and date tapes. As the cams 85 and 86 are directly connected to the driving drum shaft 76 of the day tape, the movement of the day driving drum shaft will move the cams 30 approximately 180° so as to open the completed circuit to the day and date motor and close its associated switch preparatory to the following day's operation. This operation is repeated daily. As the day and date exhibitors are 35 mechanically connected by means of an over-running clutch, such as illustrated at 28 in the previously described circuit, each daily operation of the day and date motor will advance each exhibitor one step.

40 During the short month of February, the regular day to day operation will function until midnight of the 28th is reached. At this time the pin 87 will drop into the notch 88 closing spring switch 89 supplying current through leap 45 year switch 73 which is normally closed, and the current then flows through contact springs 90 and 91, which are closed by reason of the pin 92 then being in the "February" notch in year disc, to the auxiliary motor 81 causing it to operate and drive the date exhibitor and its associated date discs 63 and 64 until the 1st is reached. At this point the circuit will be opened by the action of the switch 72 controlled by the date disc 64, by reason of the pin 93 dropping into 50 the notch 94 and causing the auxiliary motor 81 to cease functioning. Thus the date is changed from the 28th to the 1st. This action will take place on each February, excepting leap years.

On February of leap years, the regular day to 60 day operation will take place until midnight of the 28th, at which time contact 89 will be closed by reason of the pin 87 dropping into notch 88 supplying current to the leap year switch 73 but as this switch is then opened by reason of the 65 cam 68, driven by a four-to-one ratio of gears from the month disc shaft 67 no auxiliary motor action will take place until midnight of the 29th when the regular daily operation will have caused the pin 87 to drop into notch 95 closing contact 70 spring 96, supplying current through contact springs 90 and 91, which are closed since pin 92 is in the "February" notch, to auxiliary motor 81 completing the circuit thereto and causing it to operate and drive the date exhibitor and its 75

associated date disc 63 for a sufficient distance to change the date exhibitor from the 29th to the 1st. At this point the circuit will be opened by the action of the switch 72 controlled by the 5 date disc 64, as previously described, causing the auxiliary motor 81 to cease operation.

During thirty-day months, the regular day to day operation will take place as previously described until midnight of the 30th is reached. 10 At this time, the regular daily operation will function causing a movement of the date disc 63 causing pin 87 to drop into the notch 97 closing spring switch 98 thus supplying current to spring switches 99 and 91 which are closed by reason 15 of pin 92 having dropped into one of the notches on the disc 66, other than the February notch, which is deeper than the others. Current then flows through said spring switches 99 and 91 to the auxiliary motor 81 completing the circuit 20 thereto and causing it to operate and drive the date exhibitor and its associated contact disc 63 until the 1st of the month is reached. At this point the circuit will be opened by action of the switch 72 on the date disc 64. This action is 25 repeated during each thirty-day month to change the exhibitor from the 30th to the 1st. On thirty-day months, during the regular day to day operation, pin 87 drops successively into notches 88 and 95 without thereby closing any separate circuit due to the other switches associated there- 30 with being open.

To change the month exhibitor, the regular daily operation will function moving the date disc 64 associated with the date exhibitor until the 35 pin 93, at approximately six degrees prior to the termination of each cycle of the disc, engages with and is raised by cam 101 when the contact 100 will be closed completing the circuit to the month motor 82, causing it to operate. The 40 month motor moves its exhibitor with its associated month contact disc 66 and cam 102 which is directly connected to the driving drum shaft 75 of the month exhibitor. Current to the month motor is then supplied through contact 45 100 until the circuit is broken on the 1st of the month by action of the switch 72 on the disc 64. During this operation, cam 102 has been moved sufficiently to close switch 74 which in turn also feeds current to the month motor 82 until it has 50 driven the month exhibitor a sufficient distance to display the name of the following month. Cam 102 has then moved approximately 180°, opening switch 74 and causing the month motor to cease operating.

55 Having thus described our invention, what we claim and desire to secure by Letters Patent, is:

1. In a changeable exhibitor of the calendar type which is actuated by a periodic device and which includes exhibitor means for indicating the day of the week, the date of the month, and the month, means for imparting a coordinated step-by-step movement of said exhibitor means, means whereby the day of the week exhibitor cannot move without the date of the month 60 exhibitor being moved simultaneously therewith, said last mentioned means permitting independent movement of the date of the month exhibitor, and auxiliary means for moving said date of the month exhibitor independently.

70 2. In a changeable exhibitor of the calendar type which is actuated by a periodic device and which includes exhibitor means for indicating the day of the week and date of the month, operating means for moving said exhibitor means, means associated with the periodic device for causing

the operating means to function, and means associated with the day of the week exhibitor for causing the operating means to cease functioning.

3. In a changeable exhibitor of the calendar 5 type which is actuated by a periodic device and which includes exhibitor means for indicating the day of the week and date of the month, electrically operated means for moving said exhibitor means, switch means associated with the periodic device for causing the operating means to function, and switch means associated with one of said exhibitors for causing the operating means to cease functioning.

4. In a changeable exhibitor of the calendar 15 type and which includes exhibitor means for indicating the day of the week and date of the month, cooperatively associated shafts upon which said exhibitor means operate, single means for intermittently operating said exhibitor means 20 simultaneously, and auxiliary means for operating the date of the month exhibitor means independently of the day of the week exhibitor means.

5. In a changeable exhibitor of the calendar 25 type and which includes exhibitor means for indicating the day of the week and date of the month, cooperatively associated shafts one for each of said exhibitor means, single means for moving both exhibitor means simultaneously, 30 means upon said shafts permitting the date of the month exhibitor to move independently of the day of the week exhibitor to compensate for short months and leap years, and means for moving the date of the month exhibitor independently. 35

6. In a changeable exhibitor of the calendar type which is actuated by a periodic device and which includes exhibitor means for indicating the day of the week, date of the month, and 40 month, electrically operated means for moving said exhibitor means, means for starting and means for stopping said operating means, and means permitting and auxiliary operating means for moving the date of the month exhibitor independently of the day of the week exhibitor. 45

7. In a changeable exhibitor of the calendar type which is actuated by a periodic device and which includes exhibitor means for indicating the date of the month and the month, operating 50 means for imparting a step-by-step movement of said exhibitor means, switch means associated with the date of the month exhibitor means for causing the month operating means to function, and switch means associated with the month 55 exhibitor means for causing said operating means to cease functioning.

8. In a changeable exhibitor of the calendar type which is actuated by a periodic device and which includes exhibitor means for indicating the date of the month and the month, operating means for moving said exhibitors, auxiliary operating means for moving the date exhibitor to compensate for short months, means associated with the date of the month and the month exhibitor means to cause the auxiliary operating means to function, and means associated with the date exhibitor means to cause the auxiliary operating means to cease functioning. 65

9. In a changeable exhibitor of the calendar 70 type which is actuated by a periodic device and which includes exhibitor means for indicating the date of the month and the month, means for operating said exhibitors, leap year compensating means mechanically operable by the date 75

of the month exhibitor, switch means associated with said compensating means and connected with said operating means for regulating said exhibitors to compensate for leap years.

- 5 10. An electric circuit for control of an automatic calendar actuated by a periodic device and including a source of electric energy, day exhibitor means, date exhibitor means, and month exhibitor means, independent motors for operating each of said exhibitors, means to compensate for long and short months operated by the day and date means, means to compensate for leap years operated by the month means, switch means actuated by the periodic device for start-

ing one of said motors and means actuated by the day exhibitor means for stopping said last mentioned motor.

11. In a changeable exhibitor of the calendar type which is actuated by a periodic device and which includes exhibitor means for indicating the day of the week, operating means for moving said exhibitors, switch means associated with said periodic device for causing said operating means to function, and switch means associated with said exhibitor means to cause said operating means to cease functioning.

REGINALD J. SHARPE.
